UNITED STATES PATENT OFFICE.

NICHOLAS PARENT, OF CORNWALL, CONNECTICUT.

ADJUSTABLE HANGER FOR SHAFTING.

SPECIFICATION forming part of Letters Patent No. 269,537, dated December 26, 1882.

Application filed November 3, 1882. (No model.)

To all whom it may concern:

Be it known that I, NICHOLAS PARENT, a citizen of the United States, residing at Cornwall, in the county of Litchfield and State of Connecticut, have invented certain new and useful Improvements in Adjustable Hangers for Shafting; and I do hereby declare that the following is a full, clear, and exact description of the same, reference being had to the annexed drawings, making a part of this specification, and to the letters and figures of reference marked thereon.

Figure 1 of the drawings is a perspective view; and Fig. 2, a side elevation, partly in section, of my invention.

This invention relates to certain new and useful improvements in shaft-hangers; and the object thereof is to produce such a device that may be readily attached to a post, ceiling, wall, or other support by which the shafting connected therewith may be adjustably hung in either a horizontal, vertical, or oblique position, and readily changed from one such position to another, while at the same time, by the means hereinafter described, the said shafting will always be kept in line without binding. The objects I attain by the construction substantially as shown in the accompanying drawings, and hereinafter described and claimed.

In the drawings, A represents a suitable base, that may be securely attached to a post, wall, ceiling, or other place by suitable bolts or screws passing through the holes a therein. Projecting from this base A, and forming part of the same, are arms B, uniting in the form of a V with a sleeve or socket, C, at their point of union. In this sleeve or socket C works the cylindrical shank b of the hanger D, said shank being tapped to admit of the screw-threaded end of a rod, E, engaging therewith for the purpose of actuating said hanger in a direction to or from this sleeve or socket. This screw-rod E has a collar, e, resting against a shoulder, d, in the sleeve or socket C, which effectually prevents it from falling or being drawn out when the hanger is removed, and is operated by a hand-wheel, F.

The hanger D is composed of a web, e, cast with the cylindrical shank b, said web terminating in sockets f g. A bearing, G, formed

of two sections, in the usual manner, is held between the sockets f g, which form a part of the hanger D. The upper one of the sections of the bearing G is formed with a socket or countersink to receive the end of a screw, h, which passes through and engages with a screw-threaded hole in socket f. The lower section of the bearing G is cast with a shank, n, which passes into the socket g, a screw, m, engaging with screw-threads in the socket serving, like the screw h, to hold the sections of the bearing in position after centering them, a set-screw, i, holding stationary the lower section of the bearing, both the screws h m being provided with jam-nuts k. A set-screw, l, enters the socket C and abuts against the cylindrical shank b of the hanger to prevent it from twisting or turning after having been adjusted to the shafting by means of the screw-rod E, engaging therewith.

It will be seen that this hanger may be readily and truly adjusted and centered with the shafting by means of the screw-rod E and screws h m, and when such adjustment and centering have been accomplished will be firmly held in any desired horizontal, vertical, or oblique position, while by having the screw-rod operated by a hand-wheel the adjustment of the hanger in a direction to or from the socket of the base is more quickly and accurately performed than by the means heretofore employed.

Having now fully described my invention, what I claim, and desire to secure by Letters Patent, is—

The base or frame of a hanger, having socket C, and screw-rod E, and set-screw l, in combination with the hanger D, cast with screw-threaded sockets f g, and shank b, fitting within the socket C, said shank being tapped to admit of the screw-threaded end of the rod E engaging therewith, substantially as and for the purpose set forth.

In testimony that I claim the above I have hereunto subscribed my name in the presence of two witnesses.

NICHOLAS PARENT.

Witnesses:

CHARLES A. MILLER,
ARTHUR D. WARNER.
